UNITED STATES PATENT OFFICE.

CHARLES M. STEVENSON, OF HARVARD, ILLINOIS.

STRAW-CARRIER FOR THRESHING-MACHINES.

SPECIFICATION forming part of Letters Patent No. 633,625, dated September 26, 1899.

Application filed September 19, 1898. Serial No. 691,338. (No model.)

To all whom it may concern:

Be it known that I, CHARLES M. STEVENSON, a citizen of the United States of America, residing at Harvard, in the county of 5 McHenry and State of Illinois, have invented certain new and useful Improvements in Straw-Carriers for Threshing-Machines, of which the following is a specification.

My invention relates to improvements in 10 the straw-elevator attached to the rear or "tail end" of a threshing-machine, which is commonly called the "straw-carrier;" and the purpose of the invention is to cause the carrier to deliver the straw at any desired spot 15 with greater certainty. In operation these straw-carriers serve to receive the straw from the thresher and carry it to and deposit it upon a "stacker" or into a shed or other enclosure, and sometimes even to deliver it to 20 the stack, although ordinarily an auxiliary device is employed for the latter purpose. In all of these uses it is important that the straw be deposited with certainty at the point desired, and great difficulty has been 25 encountered because of the tendency of the wind to blow the straw away from such point. This difficulty I have overcome by means of an attachment applied to the carrier, which may be adjusted to carry the straw wherever 30 desired.

The invention is illustrated in the drawings presented herewith by means of seven figures, of which—

Figure 1 is a perspective view of the tail 35 end of a threshing-machine provided with my improvements. Fig. 2 is an enlarged detail of a portion thereof in side elevation. Fig. 3 is a detail perspective of certain separated parts. Fig. 4 is a sectional view looking 40 downward from the line 4-4 of Fig. 2. Fig. 5 is a sectional view in line 5-5 of Fig. 2 looking in the direction of the arrow 5. Fig. 6 is a vertical longitudinal section of the entire apparatus in line 6-6 of Fig. 7, and Fig. 7 is 45 a plan of the same with the hood removed.

Referring to the figures, A is the frame of an ordinary thresher, B the straw-carrier, attached to the rear thereof, and C C' the ordinary ropes, by means of which said straw- 50 carrier is sustained at any desired angle. An ordinary straw-elevator D, composed of three belts and cross-slats, is run by a shaft E at

the lower end and passes over pulleys e upon a shaft E' at the upper end. To the latter end of the carrier and upon the opposite sides 55 thereof I secure two brackets F F', fastened to the carrier by means of holes f, through which suitable bolts are passed and bored at f' to receive the shaft E'. At the lower extremity of a depending portion f² is a laterally-extending boss f³, also bored at f⁴, to receive a shaft G. (See Fig. 2.) The boss itself serves as a pivot for a plate H, secured to a pivoted extension O of the carrier B, and in an upwardly-extending portion of the 60 bracket is journaled a pulley I, over which is run a rope or wire J, fastened to the extension O at o and wound upon a windlass K, journaled in the frame of the straw-carrier. The windlass serves to raise or lower the free end 65 of the extension O and the wire to sustain said extension when in operation. The extension O is provided with a hood o', having a comparatively large mouth o² and a contracted discharge-opening o³ directed downward and 70 formed by carrying the top of the hood down substantially to the plane of the extension O. Said extension O is provided with a conveyer o⁴, constructed like the elevator of the straw-carrier and run by means of the shaft G, 75 which is geared to the shaft E' by means of sprocket-wheels e' g and a sprocket-chain L. As the extension O swings upon the axis of the shaft G, this gearing is not disturbed by the adjustment of the extension to any de- 80 sired angle, and therefore such adjustment can be made without stopping the machine. This is a great advantage because of the saving of time effected. Furthermore, when the machine is to be transported the extension 85 can be swung down as seen in Fig. 6, or, indeed, still farther, and secured beneath the straw-carrier without disturbing any of the belts. A pair of hooks M upon the end of the extension are adapted to engage staples 90 N of the carrier to hold the extension in the last position.

The invention is of especial value when the straw is to be delivered to a stacker or discharged through a suitable opening into a 100 shed, for in these cases whatever straw is blown aside from the stacker or the opening must be gathered up and carried to the proper place by hand. It will be seen that the ordi-

nary straw-carrier (shown at B) discharges the straw in the best possible position for the wind to catch it—that is to say, it is projected in an upward direction, so that its momentum tends to carry it beyond and above the end of the carrier, and it is only after said momentum is lost that it falls downward. The extension O receives the straw from the carrier, checks the upward movement by means of the hood o', which at the same time shields the straw from the wind and afterward, as the straw falls downward, projects it directly toward the desired spot. The extension is vertically adjustable at its free end, so that it may be brought down as near to the stacker as is practical without interfering with the passage of the straw.

The pivoting of the extension upon the boss f^3 frees the shaft G from the weight thereof and reduces the friction caused by the rotation of said shaft.

While the construction above described is the preferred one, I recognize the fact that great variation therefrom is possible without departing from the principle of the invention, and therefore desire not to limit myself to

the exact form and arrangement of parts herein shown.

I claim as new and desire to secure by Letters Patent—

The combination with a straw-carrier, of the brackets, F, F', downwardly-extending arms, f^2 , upon said brackets, perforated bosses, f^3 , upon said downwardly-extending arms, upwardly-extending arms upon said brackets, 35 pulleys, I, journaled in the upwardly-extending arms, an extension-carrier, O, pivoted upon the bosses, f^3 , and wires running over said pulleys connected at one end to the extension-carrier and adjustably secured at 40 their opposite ends to permit of the adjustment of the extension; substantially as described.

In witness whereof I have hereunto set my hand, at Harvard, in the county of McHenry 45 and State of Illinois, this 24th day of August, A. D. 1898.

CHARLES M. STEVENSON.
